UNITED STATES PATENT OFFICE.

CHARLES HANSEN, OF JOHANNESBURG, TRANSVAAL, SOUTH AFRICA.

ATTACHMENT FOR ROCK-DRILLS FOR SUPPLYING WATER THERETO.

1,138,214.

Specification of Letters Patent.

Patented May 4, 1915.

Application filed November 14, 1914. Serial No. 872,175.

To all whom it may concern:

Be it known that I, CHARLES HANSEN, a subject of the King of Great Britain, and resident of Johannesburg, Transvaal Province, Union of South Africa, have invented 5 certain new and useful Improvements in Attachments for Rock-Drills for Supplying Water Thereto, of which the following is a specification.

10 This invention relates to means or contrivances for supplying water through the bits, drills or steels of rock drilling machines to holes as they are being formed by such machines.

15 The objects of the invention are to provide an attachment which while being simple in construction, efficient in operation and inexpensive to manufacture, will lend itself to the quick and easy disengagement of the 20 water supply pipe from the machine, and so facilitate the removal of the drill, bit or steel; to insure that a practically water-tight joint shall be made between the water supply pipe and the bit, drill or steel; to supply means which shall not be unduly susceptible to the vibration set up by the rock-drill when in operation and so be worn out 25 quickly as a result of such vibration, and, if desired, to obviate the shanking of the end 30 of the drill or bit, which is necessary with some attachments as at present constructed.

The invention will be fully described with the aid of the attached drawings in which—

35 Figure 1 is a side elevation of a known type of rock drilling machine equipped with the invention. Fig. 2 is a part sectional elevation of the front head of the machine and the water supplying attachment drawn to an enlarged scale and Fig. 3 is a front 40 elevation of Fig. 2.

In Fig. 1 of the drawings, the rock drilling machine is denoted by the numeral 1, 2 representing the front head thereof which, as shown, is resiliently bolted to the main 45 cylinder 3 of the machine.

4 is the bit, drill or steel which projects through an axial hole 2^a through the head 2, and receives at its inner end 5, either directly or indirectly, the impacts of the 50 hammer piston of the machine in a manner that is well understood.

I employ a hollow drill steel, that is to say a drill steel which is provided with an axial hole or other longitudinal hole or passage 4^a which extends from a point near its rear end to and through the cutting end of the drill

steel. This hole or passage is utilized as a conduit through which the water is conducted to or in proximity to the cutting end 4^b of the drill or bit 4. Although I prefer 60 to employ the ordinary hollow steel having one longitudinal hole in it, as shown, it is to be understood that my invention is equally applicable to a drill steel having a plurality of longitudinal holes. 65

In the shank or rear end of the drill steel, there is formed a transverse preferably forwardly inclined hole 4^c which at its inner end communicates with the longitudinal passage 4^a. A plurality of the transverse holes 70 4^c may be provided if desired. The transverse hole 4^c is preferably of smaller diameter than the longitudinal hole 4^a. The shank or that portion of the drill steel 4 which is projected into the front head 2^a 75 is shown constructed with two flat sides 6, 7, and rounded at the top and bottom as indicated at 8, 9 to loosely fit the hole 2^a through the head which hole is of similar shape. The transverse hole 4^c, at its outer end terminates preferably in one of the rounded sides 80 of the shank. Ordinary steel of hexagonal, octagonal or other section may be used to obviate shanking. The front head 2 is constructed with two bosses or projections 10, 25 11 positioned at opposite sides of the front head. A hole 12 is formed through the boss 10, which hole communicates with the axial hole 2^a and a hole 13 is formed in the other boss 11 and in said hole is shrunk or otherwise fixed an eye-piece 14. The hole 12, as shown in Fig. 3, communicates also with the transverse hole 4^c in the shank of the drill 90 steel 4.

15 is a portion of the hose or other flexible pipe which is employed for conveying the water to the drill. The end of the pipe 15, as is clearly shown in Fig. 2, is projected into the hole 12 and abuts the shank of the steel around the transverse hole 4^c which it 100 completely surrounds and incloses, the flexibility of the pipe 15 permitting the end to accommodate itself to the contour of the rounded portion 8 of the shank through which the hole 4^c passes. 105

In the interior of the flexible pipe 15, there is placed a piece of rigid tubing 16, the external diameter of which may be slightly greater than the internal diameter of the hose pipe so that some force is necessary to place it in position in the end thereof. A small portion of the hose pipe 15 is

allowed to project beyond the outer end of the rigid tube 16 so as to allow of contraction of the pipe 15 when it is pushed into the hole 12. The ends of the tube 16 are preferably rounded, as shown, to prevent it cutting or otherwise damaging the hose pipe 15. As previously explained, and shown in Fig. 2, when the end of the hose pipe 15 is projected into the hole 12, its inner end forms a water-tight joint around the transverse hole 4° and thereby effectively prevents leakage of the water at that point. The inner portion 12^a of the hole 12 is made elliptical or oval, the longer or major axis being parallel to the axis of the drill steel. This admits of the movement of the inner end of the pipe 15 with the drill steel 4 when the latter is struck by the hammer piston.

20 17 is a ring or tubular piece which encircles the hose pipe 15 and partially enters the hole 12. This ring or piece 17 operates to prevent undue expansion of the hose pipe when its extremity is forced into contact 25 with the drill steel or bit and also serves to protect such hose pipe. The ring 17 extends for a short distance beyond the outer end of the tube 16 in one direction and in the opposite direction extends to a clamp 18—30 about to be described. The clamp 18 is secured around that portion of the hose pipe 15 in which the tube 16 is placed. It is shown comprising two parts connected together by bolts 19, 20. This clamp 18, as is shown, is preferably arranged in a direction parallel with the axis of the drill steel or bit. The clamp 18 is constructed on two opposite sides with lugs or projecting parts 21, 22, each having a hole formed through it.

40 23 is a U bolt or bow piece, the threaded extremities of which are passed through the holes in the lugs 21, 22 and secured therein by means of nuts 24, 25. The bow or bend of the U bolt 23 passes over the front head and is 45 loosely attached to a lever 26 as for example by passing it through a hole 27 in the enlarged end 28 of said lever. The lever 26 is loosely pinned to the eye-piece 14 by means of a pin 29 so that said pin 29 serves as the fulcrum for the lever. The lever lies parallel with the axis of the drill steel and as shown in Fig. 3, it is bifurcated at its enlarged inner end to receive the eye-piece 14.

50 As will be readily understood on reference 55 to the drawings, the movement of the lever 26 in one direction, through the medium of the U bolt 23 draws the clamp 18 and through it the water supply pipe 15, in the direction of the drill steel 4, and so forces 60 the inner end of the flexible pipe against the drill steel 4; the clamp 18 on the water supply pipe being so adjusted that sufficient contraction of the flexible pipe 15 is permitted to keep it pressed tightly against the 65 drill steel around the transverse hole 4° to

prevent leakage. The lever 26 is shown in the position in which it is placed to make a water-tight joint between the flexible pipe 15 and the shank of the steel 4 around the hole 4°. When it is desired to remove the 70 drill 4 the lever 26 is moved forward around the fulcrum 29 through an angle of 180° more or less into its other extreme position. This moves the flexible supply pipe 15, through the U bolt 23 and clamp 18, in a 75 direction away from the drill steel 4 and so allows of the easy removal of the latter.

As shown in Fig. 2 the center of the hole 27 is at the rear of the center of the fulcrum pin 29 when the lever 26 is in the position in which it is shown in Fig. 2. This results in the lever 26 being locked against unintentional release. The pull of the hose pipe on the U bolt 23 tends to keep the lever 26 in its locked position.

85 What I claim as my invention and desire to protect by Letters Patent is:—

1. In a rock drill attachment of the nature indicated in combination a rock drill a drill steel mounted in the front end of said drill, said drill steel having a longitudinal passage and a transverse passage communicating therewith, the drill having an opening which communicates with said transverse passage, a flexible water supply pipe the extremity of which is projected into the opening in the drill and surrounds the transverse passage in the drill steel and means for forcing the end of said flexible pipe into said opening to form a water-tight joint between it and the drill steel around the transverse hole.

100 2. In a rock drill attachment of the nature indicated in combination a rock drill a drill steel mounted in the front end of said drill, said drill steel having a longitudinal passage and a transverse passage communicating therewith, the drill having an opening which communicates with said transverse passage, a flexible water supply pipe the extremity of which is projected into the opening in the drill and surrounds the transverse passage in the drill steel and means for forcing the end of said flexible pipe into said opening to form a water-tight joint between it and the drill steel around the transverse hole, said means serving also to retain the flexible pipe in contact with the drill steel.

110 3. In a rock drill attachment of the nature indicated in combination a rock drill a drill steel mounted in the front end of said drill, said drill steel having a longitudinal passage and a transverse passage communicating therewith the drill having an opening which communicates with said transverse passage, a flexible water supply pipe the extremity of which is projected into the opening in the drill and surrounds the transverse passage in the drill steel, said opening in the drill steel around the transverse hole, said means serving also to retain the flexible pipe in contact with the drill steel.

drill permitting of slight movement of that end of the flexible pipe which is in contact with the drill steel and means for forcing the end of said flexible pipe into said opening to form a water-tight joint between it and the drill steel around the transverse hole, said means serving also to retain the flexible pipe in contact with the drill steel.

4. In a rock drill attachment of the nature indicated in combination a rock drill a drill steel mounted in the front end of said drill, said drill steel having a longitudinal passage and a transverse passage communicating therewith the drill having an opening which communicates with said transverse passage, a flexible water supply pipe the extremity of which is projected into the opening in the drill and surrounds the transverse passage in the drill steel, means for forcing the end of said flexible pipe into said opening to form a watertight joint between it and the drill steel around the transverse hole and means for preventing lateral expansion of the end of the flexible pipe when it is forced into the opening in the drill.

5. In water supplying attachments for rock drills the combination of a drill and a drill steel, the latter having a longitudinal hole and a transverse hole communicating therewith and the machine having an opening communicating with said transverse hole, a flexible water supply pipe, the end of which is projected into the opening in the machine so that it communicates with the transverse hole and means comprising a clamp fixed to the flexible pipe, a bow and a lever, the bow being attached to the clamp and loosely connected to the lever and the lever being pivotally attached to the machine at the opposite side to the flexible pipe for fixing the latter to the machine, as set forth.

6. In a device of the character described in combination a rock drill, a portion of which has a bore to receive the drill steel or bit and an opening communicating with said bore, a drill steel or bit having a longitudinal and transverse holes, the transverse hole communicating with the opening in the head, a flexible water supply pipe, the end of which is projected into the hole in the head and surrounds and incloses the transverse hole in the steel, a ring or cylindrical

piece surrounding a portion of the flexible pipe to prevent lateral expansion of the latter when it is forced into the hole in the head, and means for forcing the end of the flexible pipe into a hole in the head said means comprising a clamp fixed to the flexible pipe, a bow and a lever, the bow being attached to the clamp and loosely connected to the lever and the lever being pivotally attached to the machine at the opposite side to the flexible pipe for fixing the latter to the machine, as set forth.

7. A device of the character described in combination a drill head having a longitudinal bore and a transverse opening communicating with said bore, a drill steel supported by said head, said steel having a longitudinal passage and a transverse passage communicating with said longitudinal passage, the transverse passage communicating with the transverse opening in the head, a flexible pipe placed in the opening and surrounding the inlet of the transverse hole in the steel, a rigid tubular piece placed in the end of the flexible pipe, a clamp fixed around the flexible pipe and rigid tubular piece, a ring or hollow cylindrical piece placed around the flexible pipe between the clamp and the front head and partially entering the opening in the latter, the opening in the front head at its inner end being of oval shape to permit of movement of the end of the flexible pipe with the drill steel, a U bolt or bow fixed to the clamp and passing around the head, a lever fulcrumed to the head through a hole in which lever the U bolt or bow passes the fulcrum of the lever and the hole through which the bolt or bow passes being so positioned relative to each other that the lever in its one extreme position retains the flexible pipe in the opening in the head around the transverse hole in the steel and when moved to a sufficient extent in the direction of its other extreme position permits the drill steel to be readily withdrawn from the head, as set forth.

In testimony whereof I have signed my name to this specification in the presence of two subscribing witnesses.

CHARLES HANSEN.
